UNITED STATES PATENT OFFICE.

FRANK GUILDENER, OF CATONSVILLE, MARYLAND, ASSIGNOR TO SARGENT & COMPANY, OF NEW HAVEN, CONNECTICUT, A CORPORATION OF CONNECTICUT.

DESIGN FOR A PADLOCK OR SIMILAR ARTICLE.

Application filed January 13, 1923. Serial No. 4,874. Term of patent 14 years.

To all whom it may concern:

Be it known that I, FRANK GUILDENER, a citizen of the United States, residing in Catonsville, Baltimore County, Maryland, have invented a new, original, and ornamental Design for a Padlock or Similar Article, of which the following is a specification, when taken in connection with the accompanying drawings, of which—

Fig. 1 is a front elevational view of a padlock shackle embodying my design;

Fig. 2 is a side view of the same.

The shackle is regarded as the special feature of the design.

What I claim is:

The ornamental design for a padlock or similar article as shown.

FRANK GUILDENER.
